UNITED STATES PATENT OFFICE.

CHARLES S. HARDY, OF SAN DIEGO, CALIFORNIA.

REFRIGERATOR-CAR.

SPECIFICATION forming part of Letters Patent No. 593,886, dated November 16, 1897.

Application filed August 17, 1896. Serial No. 602,941. (No model.)

To all whom it may concern:

Be it known that I, CHARLES S. HARDY, of San Diego, in the county of San Diego and State of California, have invented a new and 5 useful Improvement in Refrigerator-Cars, of which the following is a specification.

My invention is an improvement in refrigerator-cars, and has for an object to provide a novel construction by which to utilize space 10 in a refrigerator-car when same is not in use as a refrigerator-car; and the invention consists in certain novel constructions, combinations, and arrangements of parts, as will be hereinafter described, and pointed out in the 15 claims.

In the drawings, Figure 1 is a perspective view of the interior of a car provided with my improvements, parts being broken away and others shown in section. Fig. 2 is a horizontal section on about line 2 2 of Fig. 3, and Fig. 3 is a vertical section on about line 3 3 of Fig. 2.

In the construction shown I provide at each 25 end of the car an ice box or receptacle A, which in general respects are somewhat similar to the end ice-box shown in my former patent, No. 509,806, dated November 28, 1893. As both these end boxes are alike in the floor 30 construction the description of one will answer for both, while the same or a similar draft-flue to that claimed in my former patent, No. 509,805, dated November 28, 1893, as shown under letter X, is also employed, the specific functions of which draft-flue will not be 35 herein explained beyond the interdependence existing between it and the respective parts of the ice-receptacle which are hereinafter described.

The end wall is provided with upright 40 cleats B, to which are hinged the cleats C of the floor, such cleats C being connected near their outer ends by a board or boards C', fixed to their undersides and extending far enough toward the end of the car to prevent the drippings from spattering into the storage-space 45 of the car.

The vertical or door-like walls of the ice-receptacle are composed of two sections D D, supported and constructed alike and rabbeted 50 at their meeting edges at d and suitably packed at such edges to form a tight joint.

In pivoting these end wall-sections I provide them at their outer ends with upright beams D', having stud or shaft projections d' at their opposite ends journaled in bearings D² in the 55 floor and ceiling of the car at the opposite sides thereof. These wall-sections D fold in toward the end of the car and against the sides thereof in the folded position of the ice-receptacle and out against the end of the 60 draft-flue at their upper ends in adjusting the receptacle for use in holding ice. In such adjustment the wall-sections bear at their lower edges against a stop or sill-cleat E in the floor of the car. These sections D are composed of the cleats D³ and the planking D⁴, 65 the latter only extending to the point where the floor C rests upon the cross-cleat D⁵, while some of the cleats extend at d³ to the floor and are connected by the base-bar D⁶, 70 these extensions d³ bracing and supporting the wall-sections from the floor and at the same time permitting free circulation of air, as indicated by the arrows as shown in Fig. 1.

At the left in Fig. 1 the ice-receptacle is 75 shown open for use, while at the right in said figure the floor is folded back against the side of the car and one of the wall-sections D is thrown partly back toward the side of the car. When the wall-section is set against the side 80 of the car, as shown in Fig. 2, it is held by a suitable latch F, which is shown as a spring-latch secured to the under side of the floor of the ice-receptacle. It takes up little or no room and leaves the interior of the car practically unobstructed. I make the floor in two 85 sections, so one-half of it may be operated at a time. When the ice-receptacle is opened for use, the floor-cleats fit at their free ends between the cleats of the wall-sections and rest 90 and are supported upon the cross-cleats D⁵.

Outside the hinged edges of the wall-sections I provide the upright cleats H, and the walls D swing inward and open outward and are held, when open, firmly against the cleats 95 H, the sill-cleat, and the end of the draft-flue by internal pressure received from the ice in the receptacle.

From the foregoing it will be seen that while the ice-receptacle operates efficiently as 100 such it will when not in use fold clear out of the way of an ordinary non-refrigerated cargo.

Having thus described my invention, what I claim as new, and desire to secure by Letters Patent, is—

1. An ice-receptacle for refrigerator-cars comprising the bottom hinged at its lower edge to and turning up against the end of the car and the front wall composed of vertical sections hinged vertically at their outer edges and swinging at their inner edges inward to 5 ward the end of the car and adapted when folded to hold the bottom in folded position substantially as shown and described.
2. In a car the ice-receptacle composed of the bottom hinged to the car and folding upward against the same the front sections hinged at their outer edges on vertical axes at the opposite sides of the car and turning inward toward the end of the car and arranged when so folded to hold the bottom in folded 15 position and the latches on the bottom by which to secure the front sections in folded position substantially as shown and described.
3. In a refrigerator-car, the ice-receptacle comprising the bottom hinged at its lower end and turning to and against the end of the car, and the front sections forming walls of the ice-receptacle and means for holding the 25

bottom in folded position, said front sections being hinged or pivoted at their outer ends 30 on vertical axes at the opposite sides of the car and swinging at their inner free ends in toward the end of the car and arranged when folded to rest in front of the folded bottom and hold the latter from dropping and means 35 for securing the front sections when so folded substantially as shown and described.

4. The combination of the car, the draft-flue and the floor-cleat, of the swinging floor and the vertical door-like sections adapted to 40 support said floor and opening outward against the floor-cleat and against the draft-flue substantially as shown and described.

5. The combination of the car the draft-flue and the floor-cleat, the swinging floor 45 made in sections, the vertical door-like sections corresponding to the floor-sections and having cleats to support the same when opened, and latch devices by which to hold the door-like sections closed substantially as 50 shown and described.

CHARLES S. HARDY.
